L. L. BLANCHARD

CHIMNEY

Filed April 18, 1927

FIG. 1

INVENTOR
Lester L. Blanchard

By
Ralph Burch
Attorney

UNITED STATES PATENT OFFICE.

LESTER L. BLANCHARD, OF PRESQUE ISLE, MAINE, ASSIGNOR TO CHIMNEY PER-
FECTOR COMPANY, LIMITED, OF OTTAWA, CANADA.

CHIMNEY.

Application filed April 18, 1927. Serial No. 184,629.

This invention relates to a new and useful chimney creosote eliminator and more particularly to a device adapted to cap the chimney stack.

5 An object of this invention is to provide a chimney cap having a frusto-tapered head which will shed all water or moisture from the flue outlet.

10 A further object of this invention is to provide a hollow chimney cap with a dead air chamber, which air is heated by the chimney smoke and gases in a manner to keep the exterior metal surfaces of the cap substantially warm to melt snow and ice which otherwise 15 tends to form around the chimney top with interference to the escape of smoke and gases.

A still further object of the invention is to provide a chimney cap having a depending elongated duct adapted to extend down the 20 chimney flue, which duct is provided with dual side-walls to constitute a depending dead air chamber in conjunction with the cap chamber in a manner that the hot smoke and gases of the lower chimney flue will heat the 25 air in the chamber which hot air will circulate to the extreme top of the cap and flue in a manner to heat the flue to such extent that the smoke and gas leave the stack substantially hot, thus eliminating the moisture which was 30 otherwise created by the mixing of hot gases with the cold air of the upper chimney flue and consequent creation of carbonic-acid gas and poor combustion.

35 A further object accomplished by the invention is elimination of the carbonic-acid gas in the upper flue which will permit the smoke and furnace gas to leave the chimney without fluctuation and consequently allow the heat to remain in the heating device or 40 furnace with great saving of fuel.

45 A still further object of the invention is to provide a chimney creosote and foul gas eliminator which is simple in construction, inexpensive to manufacture, efficient and durable in service, positive in action and a general improvement in the art.

50 Other objects and many of the attendant advantages will be readily appreciated as the invention becomes better understood after a consideration of the illustrative embodiment of the same and for which purpose such descriptive drawings have been hereto appended, wherein:

55 Fig. 1 is a perspective view of a chimney with the invention attached.

Fig. 2 is a fragmentary sectional view of the chimney and device.

Referring more in detail to the drawings in which similar reference numerals designate the corresponding parts throughout the 60 several views:—

It will be seen that the chimney stack 6 is provided with a flue 7 down which depends the elongated vertical duct 8 constituted by the telescoped, dual side walls 9 and 10 substantially spaced apart in fixed relation and sealed near the bottom margins by the base walls 11 in a manner to constitute the dead air chamber 12 and the vertical flue 13 adapted to constitute a section of the chimney flue 7. 70 The interior sidewalls 10 depend substantially below sidewalls 9 in a manner to direct the hot smoke and gases of the lower flue against the base-walls 11 in a manner to heat the air in chamber 12. The exterior sidewalls 75 9 terminate their vertical course at 14 and are flared outwardly to constitute the integral flange plate 15 adapted to engage the top surface of the chimney stack 6 in a manner to suspend the device. 80

The interior sidewalls 10 terminate their vertical course at 16 thus constituting the frusto peak of the cap from which they are flared outwardly in a diagonal, depending course to conjoin the remote margins 17 of the 85 integral flange plate 15 in a manner to constitute the hollow, frusto-tapered cap 18 which further constitutes a section of the dead air chamber 12.

From the remote margins 17 of the cap 18 90 depends the vertical flange 19 which is adapted to depend down the exterior margin of the chimney stack 6 in a manner to brace the top course of the stack and retain the cap-device in rigid combination and engagement 95 with the chimney.

In operation it will be obviously realized that the hot smoke and gases passing up the lower chimney flue 7 will effect and heat the air in the lower portion of the chamber 12 which heat will intensify between the metal walls 9 and 10 and circulate upwardly to the uppermost portions of the chamber 12 in a manner to heat the walls of cap 18 and the entire course of the flue 13. With such action it will be obvious that snow or the like will be melted and shed from the frusto-tapered cap 18 thus giving a clear vent to the flue and also will the smoke and gases leave the chimney in heated state thus eliminating the mois- 100 105 110 115

ture previously caused by the mixing of the hot gases with the cold air in the upper chimney flue and consequent creation of carbonic-acid gas and creosote within the flue which caused dangerous elements and bad combustion.

It will be obvious from the foregoing description that this invention is a great improvement in chimney caps and more particularly creosote and foul gas eliminators, and whilst the preferred embodiments have been disclosed, yet it is to be understood that minor details in the construction may be resorted to within the scope of what is claimed without departing from the spirit of the invention.

What I claim is:

1. A device for insertion in a chimney comprising a hollow cap mounted on and surrounding the upper end of the chimney and a duct depending from said cap, said duct consisting of spaced walls providing a dead air chamber surrounding the interior walls of the chimney closed at its lower end and communicating with the said cap.

2. A device for insertion in a chimney comprising a hollow cap mounted on and surrounding the upper end of the chimney, an air chamber composed of spaced walls depending from said cap and adapted to surround the interior walls of the chimney, said air chamber being closed at its lower end and having communication with said cap. 30

3. In combination with a chimney, an air chamber consisting of spaced walls lining the interior walls of said chimney and joined at their lower ends and a frusto-tapered hollow cap mounted on and surrounding the upper end of said chimney having communication with said air chamber. 35

4. In combination with a chimney, an air chamber consisting of spaced walls lining the upper interior walls of said chimney and joined at their lower ends and a frusto-tapered hollow cap formed integral with the upper ends of the walls of the air chamber, said cap being mounted on and surrounding the upper end of the chimney. 40

In testimony whereof I affix my signature.

LESTER L. BLANCHARD.
